[57] CLAIM

The ornamental design for a paper towel holder, as shown and described.

DESCRIPTION

FIG. 1 is a perspective view of a paper towel holder showing my new design;

FIG. 2 is a front elevational view thereof;

FIG. 3 is a side view thereof, the opposite side being a mirror image of the side shown;

FIG. 4 is a rear elevational view thereof;

FIG. 5 is an end view thereof, the opposite end being a mirror image of the end shown; and,

FIG. 6 is a perspective view thereof in an unfolded position.
